UNITED STATES PATENT OFFICE.

GEORGE W. MOORE, OF CHICAGO, ILLINOIS.

VIBRATOR.

Application filed April 13, 1925. Serial No. 22,526.

My invention relates to improvements in vibrators especially adapted to be secured to the fingers of the operator, the object of the invention being to provide a simple and efficient construction of this character which may be readily adjusted to fingers of different sizes; in which the extent of the vibration may be readily adjusted; and which may be readily and efficiently attached to or detached from a flexible shaft for operating the same.

Other objects will appear hereinafter.

The invention consists in the combinations and arrangements of parts hereinafter described and claimed.

The invention will be best understood by reference to the accompanying drawings forming a part of this specification, and in which,

- 20 Fig. 1 is a side view of the vibrator;
- Fig. 2 is a rear end view of the same;
- Fig. 3 is a front end view of the same;
- Fig. 4 is a face view of an adjusting wheel employed in the construction;
- 25 Fig. 5 is a perspective view of a locking spring employed in the construction;
- Fig. 6 is a longitudinal vertical section of the vibrator;
- Fig. 7 is a section taken on line 7—7 of
- 30 Fig. 6;
- Fig. 8 is a section taken on line 8—8 of Fig. 6;
- Fig. 9 is a section taken on line 9—9 of Fig. 6; and
- 35 Fig. 10 is a section taken on line 10—10 of Fig. 6.

The preferred form of construction as illustrated in the drawings comprising a cylindrical casing 11 provided at its rear end with a central shaft bearing 12 arranged to receive a central operating shaft 13 as shown. The casing 11 is provided with a rearwardly extending central sleeve 14 into which said shaft 13 projects where said shaft is provided with the usual socket and slot arrangement for attachment to the usual flexible shaft 15 arranged in the usual shaft casing or sheath 16 adapted to be inserted in the sleeve 14 in the usual way to engage and drive the shaft 13. The shaft casing 16 is provided with an annular groove 17 adapted to receive the inwardly turned end 18 of the limbs 19 of a coiled lock spring 20. The lock spring 20 consists of a spring wire

coiled as shown and having its ends extended to form parallel limbs 19 adapted to embrace the sleeve 14, the inwardly turned ends 18 extending through openings in said sleeve to engage the groove 17 to lock the flexible shaft in the sleeve but permitting its ready removal when desired. An annular groove 21 is provided in the sleeve 14 to receive the limbs 19 as shown in Fig. 10 and whereby the spring 20 will normally be locked in radiating position and vibration thereof prevented. Obviously, by swinging the spring 20 with the ends 18 as pivots, the sides of the groove 21 will operate as cam members to spread said limbs 19 and thus release the shaft 16 when desired. Likewise when it is desired to insert the shaft, by swinging the spring 20 the ends 18 may be withdrawn to facilitate such insertion as will be readily understood.

At the forward end the casing 11 is provided with a removable screw threaded cap 22 having central bearings 23 to receive the forward end of the shaft 13, and whereby said shaft is removably held in place in said casing. A segmental vibrating weight 24 is provided with a central reduced hub portion 25 secured to the shaft 13 by means of a pin 26, said weight 24 being arranged to revolve within the casing 11 as indicated. Cooperating with the fixed weight 24 is an adjustable weight 27 of substantially the same size, said adjustable weight 27 being provided with separated hubs 28 loosely engaging the shaft 13 on opposite sides of the hub 25. The adjustable weight 27 is provided with a slit 29 spanned by a clamping screw 30 and whereby the weight 27 may be clamped to the hub 25 in adjusted positions. By this arrangement it will be observed that the weight 27 may be readily adjusted on the shaft 13 either to oppose, partially oppose or cooperate with the weight 24. Obviously, when the weight 27 is adjusted into juxtaposition relatively to the weight 24 as shown in Fig. 7, the two weights, being equal, balance each other and there will be little or no vibration when shaft 13 is rotated. But when the weight 27 is adjusted angularly from this position such balance is destroyed and when the weight 27 is adjusted to a position closely adjacent to the weight 24 the entire weight 27 then cooperates with the weight 24 to

produce vibrations of the shaft 13. In intermediate positions the weight 27 tends to counteract partially the effect of the weight 24 and thus the extent of the vibrations may be adjusted and controlled as desired.

A clamping bracket 31 is secured to the underside of the casing 11 and sleeve 14, said clamping bracket being provided with fixed clamping bars 32 and 32'. The bar 32 is secured to the underside of the sleeve 14 by means of an integral central lug 34 and the bar 32' is secured to the underside of the casing 11 by means of the integral lugs 33, there being an open space between the lug 34 and the rear of the casing as shown. The clamping bars 32 and 32' are provided with padding 35 in the form of strips of sponge rubber, said strips being secured in place by means of hollow rivets 36, said rivets 36 being slidable through openings in the corresponding clamping bar and whereby yielding of the padding is facilitated. A sliding bar 37 is mounted to slide radially in the bracket 31 and carries at its lower end a clamping yoke 38 cooperating with the clamping bars 32 to clamp the fingers of the operator to secure the vibrator in position on the back of the hand. The sliding bar 37 is provided at its inner end with a lug or projection 39 engaging an eccentric cam groove 40 in the inner face of a knurled adjusting wheel 41 as best shown in Figs. 6 and 8. The adjusting wheel 41 is rotatably mounted on the sleeve 14 being provided at one side with an entry notch 42 adapted to pass over the lug 34 in placing said adjusting wheel in position on said sleeve. By this arrangement when the adjusting wheel 41 is turned on the sleeve 14 the clamping yoke 38 will be drawn toward or forced away from the clamping bars 32 and 32' and whereby the clamp may be readily adjusted to the fingers of the operator.

Arranged adjacent the outer side of the wheel 41 is an annular steel spring 43 provided with an entry notch 44 arranged to pass over the lug 34 in assembling the parts. The spring 43 is provided with a lug 45 engaging the notch 42 in the wheel 41 and thus locking the spring to the wheel 41 and permitting the ready assembling of the parts. The spring 43 is provided with diametrically arranged V-shaped beads or projections 46 arranged to engage radiating notches 47 in the inner face of a lock washer 48, said lock washer being arranged to fit over the sleeve 14 and provided with a notch 49 embracing the inner portion of the lug 34 and to which it is secured by means of a clamping screw 50. By this arrangement the parts will be readily locked in position on the sleeve 14 and the bracket 31 and may be readily removed by removing the lock washer 48. When the adjusting

wheel 41 is turned in adjusting the clamp to the fingers of the operator the beads 46 on the spring 43 will be caused to snap from one pair of notches 47 to another thus releasably locking the adjusting wheel 41 in adjusted positions. The arrangement disclosed constitutes a simple and effective one for the purpose and one which may be readily taken apart or assembled when desired.

In use the vibrator is attached to the back of the hand of the operator by engaging the finger clamp with the middle and third fingers, and, when attached to the flexible shaft, will cause the hand to vibrate. It is applied to the face or scalp by simply resting or rubbing the fingers or hand over the face or scalp, the vibrations caused by the unbalanced weight on the shaft 13 being thus imparted to the face or scalp or other portion of the body to which the hand is applied.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:

1. The combination with a vibrator, of finger clamping members mounted thereon, one of said members being movable to approach the other; a slide bar attached to and arranged to operate said movable member; an adjusting wheel having a cam groove in one face; and a projection on said slide bar engaging said cam groove, substantially as described.

2. The combination with a vibrator, of finger clamping members mounted thereon, one of said members being movable to approach the other; a slide bar attached to and arranged to operate said movable member; an adjusting wheel having a cam groove in one face; a projection on said slide bar engaging said cam groove; a spring adjacent the other face of said adjusting wheel; a lock member adjacent said spring, said lock member being provided with notches; and a projection on said spring engaging the notches in said lock member, substantially as described.

3. The combination with a vibrator, of a clamping bracket mounted thereon and arranged and adapted to rest against the backs of the fingers of a hand; a slide bar slidable on said bracket and arranged to pass between the fingers; a clamping yoke on the end of said slide bar arranged to engage the inner sides of the fingers; and means for adjusting

said clamping yoke toward and away from said clamping bracket, substantially as described.

4. The combination with a vibrator, of a bracket secured thereto; a stationary finger clamp member mounted on said bracket; a movable finger clamp member cooperating with said stationary finger clamp member; a slide bar attached to said movable finger clamp member and slidable in said bracket radially; an adjusting wheel rotatably mounted on said vibrator, said adjusting wheel being notched at one side to pass over said bracket, and said adjusting wheel being provided in its inner face with an eccentric cam groove; a lateral projection on said slide bar engaging said cam groove; an an-

nular spring arranged adjacent the outer face of said adjusting wheel, said annular spring being notched to pass over said bracket and provided with a projection engaging the notch in said adjusting wheel; a lock washer notched to pass over said bracket and secured thereto by a set screw, said lock washer being provided with radial notches in its face adjacent said spring; and diametrically positioned V-shaped beads formed on said spring and engaging said notches in said lock washer, substantially as described.

In testimony whereof I have signed my name to this specification.

GEORGE W. MOORE.
